UNITED STATES PATENT OFFICE

2,434,004

APPARATUS FOR CONVERTING RECIPROCAL VERTICAL MOTION INTO ROTARY MOTION

Albert A. Morton, Vancouver, Wash., assignor to Alfred A. Morton, Portland, Oreg.

Application November 20, 1944, Serial No. 564,212

9 Claims. (Cl. 272—33)

1

This invention relates to apparatus for converting vertical reciprocal motion into rotary motion applicable to rotating platforms such as are used in merry-go-rounds and other rotating platforms, and wherein the apparatus is carried by and rotated with the platform.

A further object of the invention is the provision of an apparatus of this character which may be operated successfully by a single operator at one end of the apparatus or an operator at both ends thereof.

A still further object is the provision of an apparatus of this character which is of simple, efficient, durable and inexpensive construction.

The foregoing and other objects will appear as my invention is more fully hereinafter described in the following specification illustrated in the accompanying drawings, and finally pointed out in the appended claims.

In the drawings:

Figure 1 is a plan view of my invention applied to a merry-go-round, with parts broken away for convenience of illustration.

Figure 2 is a fragmentary side view, taken on line 2—2 of Figure 1, looking in the direction indicated.

Figure 3 is a side view, taken on line 3—3 of Figure 1.

Figure 4 is a fragmentary sectional view, taken on line 4—4 of Figure 1.

Figure 5 is a sectional view, taken on line 5—5 of Figure 1.

Figure 6 is a fragmentary sectional view, taken on the line 6—6 of Figure 1, illustrating the supporting and driving assembly.

Referring now more particularly to the drawings:

The apparatus is mounted upon a stationary supporting column 1, which may be embedded in concrete 2, or fixed permanently to the ground surface in any other suitable fashion. A base plate or bracket 3 is rotatably mounted to the column 1 on a suitable bearing 4, providing free rotation about the post.

Upright frames 5 are fixedly secured to the bracket 3 by any suitable fastening means, as bolts 6. Cross or horizontal frames or beams 7 are fixedly secured to the lower ends of the frames 5 by means of bolts 8. The frames 5 are held in spaced relation by a cross frame 9 which provides an upper bearing 10 about the vertical column 1. The frames 5 and the cross frames 7 are rigidly secured together and rotated about the vertical supporting column on their bearings 4 and 10.

Two pairs of walking beams 11 and 12 are pivotally mounted to the frames 5 by a cross shaft 13 and stub shafts 14 respectively. Pivotally mounted on either end of the walking beams are vertical frames 15 and 16 by means of cross shafts 17 and 18. The assembly of the walking beams and the vertical frames constitutes a parallelogram arrangement. The frames 15 and 16 remaining in a vertical position at all times as the walking beams 11 and 12 are pivoted about the shaft 13. A-frames comprising arms 19 and 20 are pivotally attached at their one end to the cross shafts 17 and 18 and the vertical frames 15 and 16. The opposite ends 21 of the frames 15 are free to move up and down.

The cross shaft 13 has crank arms 22 fixed thereon for driving the connecting links 23, which are pivotally attached to the crank pins 24 at their upper ends as at 24, having their lower ends pivotally mounted at 25 to the A-frames 19 and 20. The cross shaft 13 has a pinion 26 keyed thereon, which engages the bevelled fixed gear 27 keyed to the vertical column 1.

On the outer free ends of the walking beams 25 I attach pedals 28 and 29 upon which the operator or operators of the merry-go-round stand. Two semi-circular platforms 30 are mounted on either side of the walking beams 12 to form part of the platforms 28 and 29. The platforms 30 are 30 rockably mounted on upright pivot supports 32, which are secured to the cross frames 7 as best shown in Figures 3 and 6. These platforms move in unison with the walking beams forming the main frame of the merry-go-round. I have not shown any seating accommodations on the platforms 30 but any suitable seating arrangement may be provided within the annular walls 30A surrounding the platforms. Across the gaps between the ends of the walls 30A I may provide 40 curved walls 31 to serve as a back rest and protection to the operator.

In operating the device, one operator stands on the platform 29 with one foot, and places his other foot on the pedal 33 located on the outer 45 ends of the A-frames 19, by placing the weight on the pedal and taking the weight off of the platform the A-frame 19 transfers the weight of the operator from the pedal end 21 to its opposite end, which is mounted upon the cross shafts 17 and 18. This places the weight on the vertical frame 16, thereby lowering this frame assembly together with the platform 28. As the weight was placed on the pedal 33 with the one foot of the operator and the weight was relieved from 50 the other foot, it permitted the frame assembly 55

15 to raise up with the walking beam, at the same time this operation takes place another operator may assist by putting his weight on the platform 28 and allowing the A-frame 20 and its pedal to raise. This of course assists the efforts of the first operator. As the pedals 33 are pushed down and the A-frames travel down vertically, the connecting links 23, which are pivotally connected to the cranks 22 causes the cross shaft 13 to rotate, rotating the driving gear or pinion 26, which in turn travels around the stationary gear 21, this in turn rotates the complete assembly about the vertical column 1.

From the above description it will be apparent that a rotary motion is imparted by the operators to the merry-go-round and at the same time an up and down movement to the platforms.

While I have shown a particular form of embodiment of my invention, I am aware that many minor changes therein will readily suggest themselves to others skilled in the art without departing from the spirit and scope of the invention.

Having thus described my invention, what I claim as new and desire to protect by Letters Patent is:

1. Apparatus of the character described, consisting of a vertical supporting column, a platform rotatably mounted upon the column, walking beams pivotally attached to said column, oppositely disposed A-frames attached at their one ends to the walking beams, the apex of each A-frame terminating in a pedal, one leg of each A-frame being connected with a crank shaft provided with a driving gear operatively engaged with a fixed gear mounted upon said supporting column, whereby up and down motion of said one leg of either of said A-frames will impart rotation to said platform and the parts carried thereby.

2. Apparatus of the character described, consisting of a vertical supporting column, a horizontal beam rotatably mounted upon the column, a circular platform carried by said beam, a vertical frame secured to and rotatable with said beam, a pair of walking beams pivotally attached to each side of said frame, a pair of vertical members pivotally attached to the ends of said walking beams to form a parallelogram, oppositely disposed A-frames connected at their one ends with said walking beams and vertical members, the apex of each A-frame terminating in a pedal, and one leg of each A-frame being connected with one end of a link whose upper end connects with a crank shaft rotatably mounted in said vertical frame, a driving gear carried by said crank shaft and operatively engaged with a fixed gear carried by said supporting column, whereby up and down motion of said one leg of either of said A-frames will impart rotation to the assembly.

3. A rotating apparatus comprising a stationary gear, a crankshaft geared thereto, a frame carrying said crankshaft and mounted for rotation around said gear, walking beams pivotally mounted for vertical movement on said frame, and means movable vertically with the ends of the walking beams to transmit up and down motions of said beams to said crankshaft to turn said crankshaft and rotate said frame.

4. A rotating apparatus comprising a stationary gear, a crankshaft geared thereto, a frame carrying said crankshaft and mounted for rotation around said gear, a pair of walking beams

pivotally interconnected for vertical parallel movement on said frame, and means for transmitting the vertical movements of the ends of the walking beams to said crankshaft to turn said crankshaft and rotate said frame.

5. A rotating apparatus comprising a stationary gear, a crankshaft geared thereto, a frame carrying said crankshaft and mounted for rotation around said gear, a pair of walking beams pivotally mounted on said frame for vertical movement, vertical members interconnecting the ends of said beams to form a parallel linkage, and means carried by said vertical members and extending along said beams to turn said crankshaft to rotate said frame by up and down motion of said beams.

6. A rotating apparatus comprising a stationary gear, a crankshaft geared thereto, a frame carrying said crankshaft and mounted for rotation around said gear, a pair of walking beams pivotally interconnected for vertical parallel movement on said frame, a platform rockably mounted on said frame to follow the movement of said walking beams, and means for transmitting the vertical movements of the ends of the walking beams to said crankshaft to turn said crankshaft and rotate said frame and platform in response to up and down motion of said beams.

7. A rotating apparatus comprising a stationary vertical column, a parallel linkage of walking beams mounted for horizontal rotation and vertical pivotal movement with respect to said column, a platform movable with said beams, a crankshaft geared to said column and operable to rotate said assembly, and means for turning said crankshaft by said vertical movement of said parallel linkage to rotate said assembly.

8. A rotating apparatus comprising a vertical supporting column, a frame rotatable on said column, a parallel linkage of walking beams mounted for vertical pivotal movement on said frame, a platform carried by said frame and movable with said walking beams, a crankshaft journaled in said frame and geared to said column to rotate said frame and platform, and means interconnecting said crankshaft and parallel linkage to cause vertical movements of said walking beams to turn said crank to rotate the assembly around said column.

9. A rotating apparatus comprising a stationary vertical supporting column, a frame rotatably mounted on said column, a crankshaft in said frame geared to said column, a pair of walking beams pivotally mounted on said frame for vertical movement, vertical members interconnecting the ends of said beams to form a parallel linkage, arms on said vertical members, and links interconnecting said arms and said crankshaft to rotate said assembly in response to up and down motion of said beams.

ALBERT A. MORTON.
